INVENTOR.

Emma Enos

UNITED STATES PATENT OFFICE

2,263,076

LOCK

Emma Enos, Klamath Falls, Oreg.

Application March 19, 1941, Serial No. 384,084

3 Claims. (Cl. 70—38)

My invention relates to locks and refers more particularly to tumbler locks or locks utilizing a multiple of locking pins.

One object of my invention is to provide a lock that has a plurality of locking pins that are placed in the locking position by means of a key so that when the key is withdrawn from the lock these pins are placed in the locking position and when the key is placed in the lock the pins are out of locking position.

Another object of my invention is to provide a lock that is operated by a sliding key that does not have to be turned at any time which key has a substantially centrally located jagged slot.

A further object of my invention is to provide a lock that has a multiple of locking pins that can be set into thousands of combinations by changing the configuration of the key slot and making the pins that move the locking pins to suit the configuration of the key.

I attain these results preferably by the means illustrated in the accompanying drawing, illustrating one application of the lock only, wherein like parts are referred to by similar numerals throughout the several views, in which:

Figure 1 is a plan of the lock showing the locking pins in the path of the movable body.

Figure 2 is a plan of the lock showing the locking pins out of the path of the movable body.

Figure 3 is an end elevation of Figure 1, taken on lines 3—3.

Figure 4 is a section taken on lines 4—4 of Figure 1.

Figure 5 is a section taken on lines 5—5 of Figure 1.

Figure 6 is a section taken on lines 6—6 of Figure 2.

Figure 7 is a plan partly broken away of the fixed cylinder.

Figure 8 is a section taken on lines 8—8 of Figure 7.

Figure 9 is a side elevation of Figure 7.

Figure 10 is a plan of a key.

The lock is comprised of a body 1 carrying a fixed cylinder 2 that is provided with a keyway 3 adapted to slidably engage with a flat key 4.

This cylinder 2 has two grooves 5 and 6 that match with the two holes 7 and 8 adapted to slidably carry the legs 9 and 10 of the U shaped slidably movable element 11, the leg 9 provided with three holes 12, 13, and 14 and the leg 10 with four holes 15, 16, 17 and 18 and a latch 19 with a spring 20 and this latch enters into a groove 21, to prevent the element 11 from leaving the body 1.

The cylinder 2 is preferably held within the body 1 by means of two pins 22 and 23, which lock into the groove 24, the pin 22 also serving to hold the plate 25, which forms the upper part of the keyway 3.

Directly below this keyway 3 are four holes 26, 27, 28 and 29, which carry the slidable locking pins 30, 31, 32 and 33, each having a pin 34, 35, 36 and 37 that project through the slots 38, 39, 40 and 41, into the keyway 3 in the path of the key 4, which key has a slot 42, so that when the key is in the opening position, as shown in Figure 2, this key will line up the pins, as shown in Figure 2 forcing them out of the path of the sliding element 11 and when the key is withdrawn, all of the locking pins will be forced into the path of the movable element 11, as clearly shown in Figure 1.

It is obvious that thousands of combinations could be made with this type of lock which uses no springs for the locking pins at all, and that this locking means could be applied to a single bolt as well as to a U shaped element as shown for the sake of illustrating the principle of its operation.

Having thus described and illustrated the preferred embodiment of my invention, I do not wish to limit myself to the exact construction or arrangement of parts shown, since it is self evident that modifications may be made therein, without departing from the spirit of the invention or scope of the claims.

I claim:

1. In a lock, the combination of a body, a centrally arranged fixed cylinder in said body, a plurality of transverse holes in said cylinder, a plurality of locking pins in said holes, a flat keyway on one side of said holes, a plurality of slots connecting said keyway with the said holes, pins in said locking pins passing through the said slots into the said keyway, and means adapted to cause said locking pins to project into and out of the path of a movable body.

2. In a lock, the combination of a body, a centrally arranged fixed cylinder in said body, a flat keyway one side of the centerline and in said cylinder, a plurality of transverse holes adjacent said keyway, a plurality of locking pins in said holes, a plurality of slots communicating with the said holes and the said keyway, a plurality of pins in said locking pins passing through said slots into said keyway, and a key adapted to arrange said locking pins into and out of the path of a movable body.

3. In a lock, the combination of a body, said

body centrally holding a cylinder, an opening adjacent the periphery of said cylinder slidably carrying a movable body, a keyway adjacent said periphery in said cylinder, a plurality of transverse holes below and adjacent said keyway, slots connecting said holes with said keyway, a plu-

5 rality of slidable locking pins in said holes, a plurality of pins in said locking pins, projecting into the said keyway, and a key adapted to move said locking pins into and out of the path of a movable body.

EMMA ENOS.
